UNITED STATES PATENT OFFICE.

STEPHEN HAINES PLUM, 2D, OF MADISON, NEW JERSEY.

PAPER-FEEDING DEVICE.

Application filed November 2, 1926. Serial No. 145,749.

This invention relates to improvements in automatic feeders for platen presses of the type and general construction of that disclosed in the United States Letters Patent 5 No. 1,584,468, dated May 11, 1926.

The particular object of this invention is to improve the feeder shown in said patent with a view of simplifying the construction, reducing the number of parts and increasing 10 the efficiency of the machine.

In the following specification and in the accompanying drawings, therefor, the said patent will be referred to for a general understanding of the invention, and only so 15 much of an automatic feeder is illustrated as is necessary to show the particular improvements aimed at.

Those parts which in the present instance are similar to like parts in the patent are 20 numbered with the same reference numerals to facilitate comparison and study.

The automatic feeder in the patent is characterized by a construction in which the paper is pneumatically separated and conveyed from the pile to a guiding rack or transfer table in front of the platen. The paper thereafter is fed from the transfer table to the platen. The pneumatic separating means or suction nozzles are pivoted 25 on a shaft which in turn is journaled in two upright swinging arms between which the suction nozzles are suspended from said shaft.

The shaft is mounted in the upper ends 35 of the arms and is swung in an overhead arc or concavely, while at the same time the nozzles are swung in a hollow arc or convexedly on said shaft between the arms. This same construction is employed in the 40 present instance, except that the arms are arranged to swing in a longer arc so as to feed the paper from the pile directly to the stop gages on the platen, thus dispensing with the paper transfer table and much 45 mechanism required for the operation thereof.

As a consequence, the present feeder is more simple in construction, more efficient in operation, of lower cost in manufacture 50 and feeds the paper directly to the bottom edge of the platen.

In the accompanying drawings which show the preferred embodiment of the invention,

55 Fig. 1 is a side view of a feeder with parts broken away and parts omitted, and

Fig. 2 is a right hand view of Figure 1 with parts omitted and parts broken away.

The present feeder, like the one in the said Patent No. 1,584,468, is particularly designed for use on a Chandler & Price job 60 platen press, without, however, being expressly limited thereto. This type of press is so well known in the art that only the briefest reference thereto is required for an 65 understanding of the invention. In the drawing in Figure 1 the press is identified by the frame 3, the platen pivot 5 and the platen 6. In Figure 2 the frame is indicated in dotted lines.

On each side of the press in front of the platen, there is secured a pair of fixed brackets 19 and 20. An inclined paper feed table 18 is arranged to rest on the said brackets on suitable stops 21. Extending from side 70 to side on the paper feed table 18 is a paper supporting shelf 22 on which the pile of paper 15 is adapted to rest, suitable front stops 23 being provided. The paper feed table 18 is adapted to be raised from the 75 brackets 19 and 20 and swung to one side and the particular construction and operation thereof is all fully described in the said patent and need not be repeated here.

The top sheet of the paper is separated 80 from the pile by means of one or more suction nozzles. The nozzle is in the form of a small hollow casting 50, Figure 2, which at its lower end carries a suitable rubber suction cup 53. The casting 50 is pivoted 85 in a suitable nozzle hanger 56 slidably mounted on a nozzle support 57 secured to a nozzle shaft 72. The nozzles and their particular construction and operation is identical with the nozzles in the said patent and 90 the parts are numbered correspondingly.

The suction nozzles are operated as follows:—The nozzle shaft 72 is journaled in two upright swinging arms 75 and 76, one 95 on each side of the feed table 18. The arms are pivoted at their lower ends at 25 and 26 on depending arm supports 27 and 28 which project from the feed table on each side thereof outside the fixed brackets 19 and 20. This particular construction is 100 novel in this application. The upper ends of the swinging arms 75 and 76 are connected across by a tube 77 and a rod 78. The arms and their connections form an oscillating or swinging nozzle carriage for operating the nozzles from a paper pickup position as shown in full lines in Figure 1 to 110

a paper delivery position as shown in dotted lines in said figure. The carriage is operated as follows.

Outside the one arm 75 the shaft 72 carries an arm 79 to which is pivoted a link 80, the other end of which is pivoted to an arm 81 which in turn is pivoted on the arm pivot 25. The arms 75, 79, 81 and link 80 form practically a parallelogram for properly oscillating the nozzle shaft 72 to position the nozzles accurately with respect to the paper and the platen. For this purpose the shaft 72 carries adjustably clamped thereto a nozzle stop 82, with a spring 83, Figure 2, which tends to move the stop and shaft 72 in a clockwise direction in Figure 1, one end of the spring acting against the stop, the other end of the spring being fast in the arm 75.

That is to say, the spring 83 tends at all times to rotate the shaft 72 upwardly and towards the paper, consequently also acts to force the three other sides of the parallelogram downward to the right in Figure 1 until the lower end of the arm 81 comes to rest upon an adjustable stop 84 mounted in the extreme lower end of the arm support 27. The nozzle stop 82 is also moved into contact with an adjustable abutment 85 adjustably carried by the connecting rod 78 by a set screw 86.

The position of the nozzles in the paper pick up position is determined by the position of the nozzle stop 82 against the abutment 85. If the latter is screwed down, the nozzles will be moved towards the platen and vice versa. In the paper delivery position, as shown dotted in Figure 1, the adjustment of the nozzles, that is the point of delivery, is regulated by the stop 84. The means for operating the nozzles are identical with those shown in the said patent. In the latter, the carriage operating means consist of a series of interconnected levers which are actuated from the connecting rod on the one side of the press by means of a relatively large bell crank. In the present instance the nozzle carriage is operated on its pivots 25 and 26 by means of a link 30 pivoted to the arm 75 at 88, while the other end of said link is pivoted to the upper end 31 of a large lever 32 pivoted at 33 to the bracket 19. The connection between the link 30 and the arm 31 is made by a removable stud 34, because, when the delivery table is to be raised and swung to one side as above mentioned, the link 30 must be temporarily disconnected from the arm.

The lever 32 constitutes a means for operating the nozzle carriage, and said lever may be suitably connected to any part of the press convenient for the purpose. This particular part is not shown because a mere matter of mechanical connection and because

the said patent clearly discloses one form 65 thereof suitable for the present purpose.

The separated sheet 65 is conveyed from the pile to the platen about as shown dotted in Figure 1 and is fed with its leading edge directly against the usual stop gages 40 on the platen. The hose connection 110 shown broken in Figure 1 constitutes a means for applying suction to the nozzles from a suitable pump, not shown. The hose is attached to the hollow shaft or tube 77 from which other, flexible, hose connections 52 lead to the nozzles.

The foregoing is thought to disclose fully the construction and operation of the invention. By comparing it with the aforesaid patent or other forms of automatic feeders it will be seen that the construction and operation is of extreme simplicity and directness and no intervening mechanism is required between the nozzles and the platen 85 for delivering the paper into printing position.

The invention has been disclosed in its preferred form, but it is to be understood that nothing hereinbefore stated is to be construed as a limitation, because changes and alterations may easily be made by those skilled in the art without departing from the spirit of the invention or the scope of the appended claims.

I claim:

1. The combination with a printing press including a platen and stop gages thereon for positioning the sheet to be printed, of means for supporting the paper, an oscillating carriage mounted on said means, paper separating means mounted on the carriage, means for operating the paper separating means to separate a sheet of paper, means on the carriage for adjusting the movement of the separating means, co-operating means on the carriage and table for regulating the movement of the carriage and means for operating the latter to cause the separating means to convey separated paper direct to the platen into printing position thereon in accord with the position of the stop gages.

2. The combination with a printing press including a platen and stop gages thereon for positioning the sheet to be printed, of paper separating and conveying means comprising paper supporting means, a suction nozzle for separating the top sheet of paper, mechanism for moving the suction nozzle from a paper pick up position to a delivery position for delivering the paper directly to the platen in contact with said stop gages, and means on the paper supporting means for adjusting the movement of the suction nozzle in over the platen to accord with the position of the said stop gages.
